[57] CLAIM

The ornamental design for a ceiling fan pull rack, as shown and described.

DESCRIPTION

FIG. 1 is a perspective view of a ceiling fan pull rack showing my new design;

FIG. 2 is a typical side elevational view thereof;

FIG. 3 is a top plan view thereof; and,

FIG. 4 is a bottom plan view thereof.

The broken line showings of ceiling fan pulls in FIGS. 2-4 are for illustrative purposes only.

FIG. 1

FIG. 2

FIG. 3

FIG. 4
